M. G. ROSENTHAL,
LAUNDRY TAG,
APPLICATION FILED DEC. 31, 1921.

1,415,713.

Patented May 9, 1922.

UNITED STATES PATENT OFFICE.

MORRIS G. ROSENTHAL, OF CINCINNATI, OHIO, ASSIGNOR OF ONE-HALF TO FRED E. KLEIN, OF CINCINNATI, OHIO.

LAUNDRY TAG.

1,415,713.

Specification of Letters Patent. Patented May 9, 1922.

Application filed December 31, 1921. Serial No. 526,171.

To all whom it may concern:

Be it known that I, MORRIS G. ROSENTHAL, a citizen of the United States, and a resident of Cincinnati, in the county of 5 Hamilton and State of Ohio, have invented certain new and useful Improvements in Laundry Tags, of which the following is a full, clear, and exact description, reference being had to the accompanying drawings, 10 forming part of this specification.

The object of my invention is to provide a construction of identification tag for articles to be laundered which shall obviate the difficulties met with in the use of the common methods of identification as far as possible and which shall combine the advantages incident to the use of one or another of the well known constructions.

The attachment of a metal or other tag to 20 goods to be washed in a laundry by clips or other permanent means of attachment is objectionable, of course, in all cases where the tag remains visible or where it is necessary under the system of identification adopted 25 to affix a new tag, each time the article is returned to the laundry. Moreover, the cost of such tags is an item of great expense in the aggregate.

The use of cloth tags sewed or otherwise 30 secured to the goods is also objectionable, because in sorting the goods, after washing, it is difficult to find the location of the label and much time is frequently lost in searching the article for the identification mark. 35 This is also an objection when the goods are simply marked with an indelible ink mark.

Moreover, for dry cleaning, when the goods are subjected to ink solvents, the mark is very apt to become obliterated.

40 These objections have resulted in many cases in the use of identification devices which may be characterized as safety pin constructions to be pinned to the goods and removed for re-use when they have served 45 their purpose.

These safety pin devices, with a plate bearing the identification mark, are also of advantage in sorting the goods, as the goods can be collected by suspending the devices 50 on rods or pins, one for each lot.

To pin the tag to many classes of goods is objectionable, however, as the pin holes formed remain; and, moreover, these devices are ordinarily so bulky as to be liable to 55 damage the laundry machines or to become

so entangled in the goods as to tear and damage the material to which they are attached.

As I have said, it is my object to combine in my improved tag the advantages, while it avoids the objections to the use of the present methods of identification, and it consists in that novel construction and arrangement to be hereinafter particularly pointed out and claimed, in which the pin method provided with means for suspension is retained, but combined with a thin and flexible tab, which tab is secured to the goods by sewing, so that the tab can be readily and easily removed without damage to the goods and without leaving any mark of attachment.

In the drawings,

Figure 1 is a perspective view of one form of my improved tag as attached to the goods.

Figure 2 is a plan view of the metal blank 75 from which this tag is formed.

Figure 3 is an enlarged transverse section illustrating the detachable method of securing the tag to the goods.

Figure 4 is a perspective view of the tag 80 illustrating another method of suspension.

Figure 5 is a plan view of the metal blank from which this tag is formed.

Figures 6 and 7 are perspective views of 85 other forms of construction.

As illustrated in Figures 1-5, I take a strip of metal or other suitable material 1, and fold it in the middle, and by teeth 2, 2, near one edge and registering holes 3, 3, at the other, I secure thereto a tab of cloth 4. 90 At the same time the metal strip is folded, for one construction, I form a head 5 so that the tag may be readily suspended on a slotted bar. Instead of forming the head 5, I provide a slot 7 in another construction 95 which serves the same purpose as a ready means of stringing the tags on a rod 6.

It will be obvious that other forms of tags can be provided, such as a tag all of one material and provided with an integral loop 8, 100 as shown in Figure 6, or where the body of the tag is of cloth provided with an eyelet 9, as illustrated in Figure 7. I have no desire to limit myself to the several constructions which I have adopted to illustrate my 105 invention, the feature of which is the flexible tab for detachably securing the tag to the goods in connection with the provision of means for suspending the tag when secured to the goods, it being not even of the essence 110

that there should be two distinct and separate materials employed in the construction, so long as the inner or attaching end of the tag merges into a soft and flexible portion, 5 which can be readily and easily sewed to the goods to be identified, and provision is made for ready suspension.

Upon the body portion of the tag an identification mark is impressed, as A 40. According to a system in vogue for using these tags, each lot of goods from the same source is given a letter and the number of lots a numeral, and the tags are to be used over and over again.

15 The body of the tag, however, is not itself secured to the goods 15 and the flexible tab is alone attached. This attachment is done preferably on a sewing machine in which a loose tension is provided for the needle 20 thread 10 and a tight tension for the bobbin thread 12. The tight thread then acts as the locking thread, running through comparatively loose loops. After the goods are washed, the thread 12 can be readily drawn 25 out and the tag set free from the goods for subsequent use.

The advantages of my construction are obvious. It combines the good points of the safety pin method; the articles can be 30 strung on the pins or other suspension devices for assembling, drying and the like; the place of attachment of the tag can be readily determined without search; the mark

can be indelibly affixed to the tag. The flat body portion presents no detrimental material to the laundry machinery; and the body portion lends itself readily to a sewing machine attachment for feeding the tags in a hopper or chute rapidly to the machine, carrying the flexible attaching tabs to the 40 machine needle where the tags can be detachably secured even more rapidly than the safety pin constructions can be pinned to the goods.

Having thus described my invention, what I claim as new and desire to secure by Letters Patent, is:—

1. A laundry tag comprising a stiff body portion, and a flexible tab attached thereto, adapted to be detachably secured by sewing 50 to the goods to be identified.

2. In a laundry tag, the combination of a metallic plate provided at its outer end with means for suspending same, and having a flexible tab attached at the other end for 55 detachably securing same by sewing to the goods to be identified.

3. In a laundry tag comprising a strip of stiff material provided with a means of suspension, and a strip of soft, flexible material 60 to which the stiff strip is permanently attached, the soft strip adapted to be detachably secured by sewing to the goods to be identified.

MORRIS G. ROSENTHAL.
